COMBINED SISSY BAR PAD AND RECEPTACLE FOR CYCLES

Henry Akers and Patricia L. Akers, both of 271 Knox
St., Costa Mesa, Calif. 92627

Filed Oct. 1, 1969, Ser. No. 19,359

Term of patent 14 years

Int. Cl. D12—14

U.S. Cl. D90—15

FIG. 1 is a front elevation of a combined sissy bar pad and receptacle embodying our design;

FIG. 2 is a side elevation thereof;

FIG. 3 is a rear elevation thereof;

FIG. 4 is a top plan thereof;

FIG. 5 is a bottom plan thereof.

We claim:

The ornamental design for a combined sissy bar pad and receptacle for cycles, as shown.
